CARL J. LINDEGREN, OF PROVIDENCE, RHODE ISLAND, ASSIGNOR TO CROMPTON & KNOWLES LOOM WORKS, OF WORCESTER, MASSACHUSETTS, A CORPORATION OF MASSACHUSETTS

SHUTTLE BOX FOR DROP BOX LOOMS

Application filed August 10, 1929. Serial No. 384,821.

This invention relates to combination or multiple shuttle boxes such as are used in a drop box loom.

It is the object of my invention to provide multiple shuttle boxes for a drop box loom so constructed that they are more economical to manufacture, lighter in weight, less liable to breakage, and generally more reliable in operation.

Specific features of the invention and certain arrangements and combinations of parts by which these results are attained will be hereinafter described and more particularly pointed out in the appended claims.

A preferred form of the invention is shown in the drawings, in which

Fig. 1 is a front elevation of portions of a loom embodying my improvements;

Fig. 2 is a plan view of the parts shown in Fig. 1;

Figs. 3 and 4 are sectional end elevations, taken along the lines 3—3 and 4—4 in Fig. 1;

Fig. 5 is an enlarged detail end elevation to be described;

Fig. 6 is a partial enlarged front elevation of certain parts;

Fig. 7 is a sectional plan view, taken along the line 7—7 in Fig. 6;

Fig. 8 is a sectional end elevation, taken along the line 8—8 in Fig. 7;

Fig. 9 is a detail sectional plan view, taken along the line 9—9 in Fig. 4 enlarged;

Fig. 10 is a detail view to be described, and

Fig. 11 is a detail sectional plan view, taken along the line 11—11 in Fig. 1.

Referring to Figs. 1 and 2, I have shown portions of a lay 10 supported on swords 11 and having the usual lay end structure 12 in which a multiple shuttle box S is mounted for vertical sliding movement. The box S is shown as having four cells for the accommodation of four different shuttles and is supported and moved vertically by a usual lifter rod 14.

My improved shuttle box is preferably formed from a number of sheet steel elements secured together by welding or in some equivalent manner.

Plates 20, 21, 22, 23 and 24 form the bottoms and tops of the several shuttle cells,

as clearly indicated in Fig. 8. These plates 20 to 24 are provided with lugs 25 adapted to be inserted in openings in a front end plate 30 and welded or otherwise secured therein.

The plates 20 to 24 also have offset projecting portions 32 (Fig. 7) extending through slots in the plate 30 and provided with lugs 33 extending through openings in a plate or bar 35 which constitutes a guard for the binders 40.

At their rear edges, the plates 21, 22 and 23 are similarly provided with lugs 36 extending through back frame members 37 and through a back end plate 38 and preferably welded therein. The plates 21, 22 and 23 are also provided with additional projections 40^a extending through spaced openings in the back frame members 37 (Fig. 9) along the length of the box and suitably secured therein.

At the back edge, the top plate 20 is provided with a down-turned flange 20^a, which in effect forms a back frame member for the top of the upper box, and the bottom 24 of the lowest box is similarly provided with an up-turned flange 24^a. The flanges 20^a and 24^a are welded to the back end frame member 38.

The member 38 is folded back upon itself at its extreme end portion to form the thickened hollow end structure indicated at 44 in Fig. 7. This portion 44 slides in a vertical guideway in the lay end structure 12, as indicated in Fig. 2.

At their left hand ends, as viewed in Fig. 2, the plates 20 to 24 are provided with flanges 50 struck up from the surface of the plates to provide bearings for an elongated screw or stud 51 on which the hubs of the binders 40 are pivoted, as indicated in Fig. 4.

The left hand ends of the plates are also provided with projections 53—54 (Fig. 11) extending through openings in a left hand front end frame member 56 and welded or otherwise secured therein.

Portions 58 of the frame members 56 are struck up, as indicated in Figs. 1, 3 and 5, to provide lugs for laterally positioning the ends of binder springs 60, which are secured

in position by screws 61 and are firmly seated between adjacent lugs 58.

The extreme end portion of the front end frame member 56 is reversely bent on itself, as indicated at 62 in Figs. 10 and 11, to provide a reinforced projection adapted to slide in a groove in the lay end structure 12. The extreme end of the reversely bent portion is preferably offset and abutted against the end 10 frame to provide a wedge-shaped section for said projection.

At their rear sides, the plates 20 to 24 are unsupported at their left hand ends except as they are re-enforced by the flanges 20^a 15 and 24^a and by the back frame members 37.

In the operation of the loom, the filling thread draws against the curved entrance portion 70 (Fig. 7) of the front frame member 30 and also against the bottom plate 80 21 to 24 of the box in which the shuttle is received.

In order that the filling may not be caught in any crack or groove between the bottom plate and the front frame member, I locate 85 the projections 25 previously mentioned at the extreme front edge of the plates 21 to 24, so that the filling engages continuous surfaces only as it is drawn from the mouth of the shuttle box.

Having thus described my improved multiple shuttle box, it will be evident that the box herein shown is of very strong construction, firmly braced and re-enforced, and that the parts, while of light weight, are of increased strength and reliability. The construction herein shown permits a reduction 35 in weight to ten to fifteen percent over the structure previously used, while at the same time increasing the strength.

Having thus described my invention and the advantages thereof, I do not wish to be limited to the details herein disclosed, otherwise than as set forth in the claims, but what I claim is:—

1. In a drop box loom, a multiple shuttle box comprising front and back end plates and a plurality of top and bottom plates, said end plates being provided with openings and said top and bottom plates being provided with 45 projecting portions extending through said openings and rigidly secured therein, one of said front end plates being provided with additional openings and said top and bottom plates having additional portions projecting 50 a substantial distance through said openings, and a flat bar in which said projecting portions are secured, said flat bar spaced from said end plate and forming a guard for the ends of a plurality of binders.

2. In a drop box loom, a multiple shuttle box comprising front and back end plates and a plurality of top and bottom plates, said plates being formed of sheet metal and each top and bottom plate having a portion in one 60 end struck up from the continuous flat sur-

face thereof to provide an integral bearing sleeve for a binder stud.

3. In a drop box loom, a multiple shuttle box comprising front and back end plates and a plurality of top and bottom plates, rigidly 70 secured together, and certain of said end plates being reversely folded to provide guiding portions slidable in the lay end.

4. In a drop box loom, a multiple shuttle box comprising front and back end plates and a plurality of top and bottom plates, rigidly secured together, and certain of said end plates being reversely folded to provide guiding portions slidable in the lay end, the ends of the reversely bent portions being offset inwardly and abutted against said end plates to provide wedge-shaped sections for said guiding portions.

5. In a drop box loom, a multiple shuttle box comprising front and back end plates and a plurality of top and bottom plates, rigidly secured together, one of said front end plates having portions struck up out of the plane of said plate to provide offset spaced abutments effective to position and confine the 80 ends of binder springs associated therewith, and means to secure said springs to said end plate.

6. In a drop box loom, a multiple cell shuttle box having front and back end plates, intermediate cell-forming plates and top and bottom cell-forming plates rigidly secured to the end plates, said top and bottom plates having portions bent perpendicular to said top and bottom plates to form side flanges 95 extending alongside and substantially across the front face of one of said back plates and permanently secured thereto.

In testimony whereof I have hereunto affixed my signature.

CARL J. LINDEGREN.
